UNITED STATES PATENT OFFICE

SAMUEL J. WYNN, OF NORWALK, CONNECTICUT, ASSIGNOR TO L. W. HOLDING CORPORATION, OF NEW YORK, N. Y., A CORPORATION OF NEW YORK

MULTIPLE FUSE

Application filed June 4, 1931. Serial No. 541,985.

This invention relates to new and useful improvements in a multiple fuse plug.

It is an object of this invention to construct a multiple fuse plug which is characterized by a core adapted to assume various rotative positions and formed with a fuse chamber for the combustion of the fuse elements, and a means on the core for selectively connecting for operation different fuse elements in different positions of the core so that in all positions of the core combustion of the fuse elements takes place in the fume chamber.

When a fuse is constructed according to the arrangement mentioned in the above paragraph, it is possible to provide a large fume chamber for the combustion of any of the fuse elements. Various attempts have been made to construct multiple fuse plugs but have met with failure in that the provision of a large enough combustion chamber for the fuse elements were not provided. Consequently, when the fuse element burnt, a flame was thrown which would extend from the fuse body itself, which is unsatisfactory. The provision of a large fume chamber correspondingly cuts down the pressure within the chamber during combustion so as to reduce any possibility of the fuse body rupturing. The size of the fuse body is limited commercially in that it must engage within conventional sockets and the provisions of one chamber which is adapted to assume various positions so as to selectively house the fuse element in operation forms the basis of this invention.

It is a still further object of this invention to arrange the core in such a manner that it shields all the other fuse elements except the one which is in connection. This arrangement prevents the flame from the "shot" fuse element from damaging any of the other elements.

Another object of this invention is the provision of a hollow body in a multiple fuse plug and having a pair of contacts and carrying a plurality of fuse elements equally spaced from each other, the fuse elements being connected up with one contact, whereby a means carried upon a core accomplishes the closing of a circuit from the one contact to

the other through any of the fuse elements.

A still further object of this invention is the provision of a means on the core of the fuse for connecting any of the fuse elements selectively with a member which is in turn connected with the shell contact.

Another object of this invention is the arrangement of fuse elements in the form of fingers integral with the base portion for connection with one of the contacts on the fuse plug. Further, to form dovetailed grooves in said fuse body and force the fingers therein so that they maintain their positions.

A still further object of this invention is the provision of a cap on the body of the fuse plug for holding the core in place.

A still further object of this invention is the provision of a handle projection or a recess in the core for providing a gripping portion to turn the core into the various rotative positions.

A still further object of this invention is the provision of means for limiting rotation of the core in one direction only so that the fuse elements are burnt in sequence.

Furthermore, as another object, this invention proposes the construction of the core in a manner to provide a main fume chamber in which the combustion of the fuse element takes place, a discharge passage from the main chamber to guide the gases from the core, and a tortuous connection with the atmosphere. Thus the main portion of the flame will be shielded within the core since the discharge to the atmosphere is possible only along the tortuous path.

As another object of this invention, it is proposed to provide a ring encircling and on the core and having a large end capable of reaching downwards to selectively engage one of the ends of any of the fuse elements depending upon the position of rotation of the core.

As a still further object it is proposed to construct each of the fuse elements of substantially U-shape in transverse section and to construct the spring mentioned in the previous paragraph similarly at one end so that the parts may interengage and form a ratchet

connection to limit rotation of the core in one direction only.

A still further object of this invention is the construction of a multiple fuse plug 5 which is of simple, durable construction, dependable in use and efficient in action, and which can be manufactured and sold at a reasonable cost.

For further comprehension of the invention, and of the objects and advantage thereof, reference will be had to the following description and accompanying drawing, and to the appended claims in which the various novel features of the invention are more particularly set forth.

In the accompanying drawing, forming a material part of this disclosure:—

Fig. 1 is a plan view of a fuse constructed according to this invention.

Fig. 2 is an enlarged sectional view taken on the line 2—2 of Fig. 1.

Fig. 3 is a sectional view of the body of the fuse, per se.

Fig. 4 is a plan view of Fig. 3.

Fig. 5 is a back elevational view of the core, per se.

Fig. 6 is a front view of Fig. 5.

Fig. 7 is a horizontal sectional view taken on the line 7—7 of Fig. 6.

Fig. 8 is a vertical sectional view taken on the line 8—8 of Fig. 6.

Fig. 9 is a horizontal sectional view taken on the line 9—9 of Fig. 2.

Fig. 10 is an elevational view of a core constructed according to a modification of the invention.

The multiple fuse, according to this invention, comprises a core 10 adapted to assume various rotative positions and formed with a fume chamber 11 for combustion of fuse elements 12 within the body 13. The core 10 has a top projecting portion 14 constituting a handle so that it may be manually turned to different rotative positions. A flange 15 at the top of the core serves to close the top end of the fuse body 13. A cap 16 is engaged over the fuse body and has its inner ends extending over the flange 15 so as to rotatively hold the core 10 in place. The lower portion 17 of the core 10 is of cylindrical form so as to tightly fit within the hollow body 13. At the top, right beneath the flange, the cylindrical body is formed with a recess 18 in which a ring 19 rests. The ring and recess are of narrow width throughout most of their length, widening only at one portion 20. The ring is formed from a metallic strip bent around the core and having its ends 19^a bent radially into a slot formed in the core 10 so as to maintain itself in place. The part 20 of the ring is cut in tongue form and is engageable against the tips of the fuse elements, shown in Fig. 2.

The combustion chamber 11 is in the core 65 and communicates with one side of the core

and at this point is of a size so as to be capable of encircling one of the fuse elements at a time. Inside within the core, the fume chamber enlarges. A discharge passage 21 communicates with the fume chamber and discharges inside of the contact ring 19. At the lower extremity, the core is formed with a small projection 22 adapted to engage with a corresponding reduced part within the fuse body 13 to guide the rotative mounting of the core. The fuse body 13 is recessed at the top, as indicated by reference numeral 23, so as to accommodate a stationary contact spring 24 insulated from the top ends of the fuse elements 12 by an insulation washer 25. The fuse elements 12 are disposed within dovetailed grooves 26 formed in the insulation washer 25 and upon the inside wall of the body 13 and extending from the recessed portion 23 downwards to the bottom of the fuse body and there integral with a base disc portion 27 which is disposed within a recess 28 formed in the bottom of the fuse body. The horizontal portions of the fuse elements, which are located on the bottom of the hollow body 13, are reduced at the points 12^a to cause fusing of the fuse elements at these points.

An end contact 29 is located upon the contact end of the fuse body on the outer side and has a stem portion 30 extending into the hollow of the fuse body. A nut 31 is threadedly engaged upon the stem 30 and serves to clamp and hold the base portion 27 of the fuse elements in place. A means is arranged upon the core 10 for selectively connecting for operation different fuse elements 12 in different positions of the core in a manner so that in all positions of the core the combustion chamber 11 is in a place selectively over the fuse elements. This means comprises the contact ring 19 which has the large portion 20 capable of extending downwards and contacting with the top ends of the fuse elements. This contacting end has a right angle 33 capable of engaging in the dovetailed grooves 26 and against the fuse elements so as to hold the core in the selective rotative position.

The contact tongue 20 also acts as a means for limiting rotation of the core in one direction only. This is so in that if the core is turned counterclockwise, the tongue 20 tends to jam and prevent counterclockwise rotation of the core, but in the event that the core is turned clockwise, the spring tends to tightly wind on the core and allows turning to various positions that are desired. For this reason, the fuse elements may be used in sequence. The contact ring 19 engages with the contact 24. This latter contact is connected with a lead 36 extending to the outside of the core body and connecting with a customary contact shell 37 on the body.

Numerals indicated by reference characters 38 are inscribed upon the top of the ring 16 so as to indicate the location of the various

fuse elements. An arrow 39 is inscribed upon the top of the projection 14 to indicate the different positions of rotation of the core. As shown in Fig. 1, the core is in the position in which fuse No. 1 is connected for use. The cap 16 is held in place by diametrically opposite tongues 40 upon the lower edge being inwards below a shoulder portion 41 formed on the fuse body 13. In Fig. 10, a modified construction of the core has been disclosed in which a recess 42 is formed at its top for receiving a turning key to turn the core. This is used in lieu of the turning projection 14. The advantage of this modified arrangement is that unauthorized persons not having the proper turning key will be at a great disadvantage to turn the core so as to reset the fuse. This will eliminate tampering. Further, an authorized person may turn the fuse to a position wherein the circuit is opened either in that one of the fuse fingers has been left blank or that the fuse has been set to a burnt out fuse element.

The operation of the fuse may be traced by assuming it in the condition shown in Figs. 1 and 2. In this condition, fuse element No. 1 will be in circuit for use, that is, an electrical circuit will exist from the end contact 29 through fuse element "1" to the ring contact 20, the contact 24, the connection 36, and finally the shell contact 37. After fuse No. 1 has been "blown", the core can be turned to its next position wherein fuse element "2" will be in circuit. The circuit would then extend from the end contact 29 through fuse element "2", the contact ring 20, the contact 24, the connection 36 and the contact shell 37. In this manner, all of the fuse elements may be selectively used. The fuse chamber 11 should be designed of such a size that the rise in pressure on combustion taking place during the blowing of a fuse does not form fire dangers. It should be recognized that the provision of a large fuse chamber which can be located selectively to connect with any of the fuse elements is of great advantage. Gases due to burning of a fuse element pass from chamber 11 through discharge 21 around ring 19, up between flange 15 and the fuse body and out from between the cap 16 and the top of the flange 15. This is a tortuous path which the flame cannot take.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit or the scope of the appended claims.

Having thus described my invention, what I claim as new, and desire to secure by United States Letters Patent is:—

1. A multiple fuse plug, comprising a hollow body supporting a pair of contacts, fuse material within the hollow body and in the form of a base portion connected with one of said contacts and having a plurality of fingers extending from the base portion and within the inner face of the hollow body, a core in intimate contact with the inner surface of the hollow body and adapted to assume various rotative positions and having a fume chamber for selective location over the fuse fingers, and a means on the core and on the fuse body for selectively connecting any specific fuse finger exposed to the fume chamber with the other contact. 70 75

2. A multiple fuse plug, comprising a hollow body supporting a pair of contacts, fuse material within the hollow body and in the form of a base portion connected with one of said contacts and having a plurality of fingers extending from the base portion and within the hollow body, a core within the hollow body and adapted to assume various rotative positions and having a fume chamber for selective location over the fuse fingers, 80 85 and a means on the core and on the fuse body for selectively connecting any specific fuse finger with the other contact, comprising a spring on the fuse body connected with said other contact, and a ring on said core engaging said spring and having an enlarged portion contacting with the tip of one of said fuse fingers. 90 95

3. A multiple fuse plug, comprising a hollow body supporting a pair of contacts, fuse material within the hollow body and in the form of a base portion connected with one of said contacts and having a plurality of fingers extending from the base portion and within the hollow body, a core within the hollow body and adapted to assume various rotative positions and having a fume chamber for selective location over the fuse fingers, and a means on the core and on the fuse body for selectively connecting any specific fuse finger with the other contact, comprising a spring on the fuse body connected with said other contact, and a ring on said core engaging said spring and having an enlarged portion contacting with the tip of one of said fuse fingers, the enlarged portion of said ring contact being shaped for engaging with correspondingly shaped portions of grooves for receiving said fingers in said body. 100 105 110 115

4. A multiple fuse plug, comprising a hollow body supporting a pair of contacts, fuse material within the hollow body and in the form of a base portion connected with one of said contacts and having a plurality of fingers extending from the base portion and within the hollow body, a core within the hollow body and adapted to assume various rotative positions and having a fume chamber for selective location over the fuse fingers, and a means on the core and on the fuse body 120 125 130

- for selectively connecting any specific fuse finger with the other contact, comprising a spring on the fuse body connected with said other contact, and a ring on said core engaging said spring and having an enlarged portion contacting with the tip of one of said fuse fingers, the enlarged portion of said ring contact being shaped for engaging with correspondingly shaped portions of grooves for receiving said fingers in said body, said shape being substantially of U form whereby rotation of the core is limited to one direction only.
5. A multiple fuse, comprising a fuse body having a pair of contacts and being opened at the top end and having an enlarged recess, a contact spring disposed within said recess, means for connecting the contact spring with one of said contacts, a core rotative within the hollow body and projecting from the opened end, means for rotatively supporting said core in place, a fuse within the body and comprising a base portion in connection with the other contact and a plurality of finger portions extending upwards in grooves in the body, means on said core for selectively connecting for operation different fuse fingers in different positions of the core with said ring, and said core being formed with a fume chamber adapted for selective location over any one of the fuse fingers.
6. A multiple fuse plug, comprising a hollow body supporting a pair of contacts, fuse material within the hollow body and in the form of a base portion connected with one of said contacts and having a plurality of fingers extending away from the base portion and within the hollow body, a core within the hollow body and adapted to assume various rotative positions and having a fume chamber for selective location over the fuse fingers, a passage from said chamber to the top of said core, and means for forming a tortuous path from said passage to the atmosphere, and means on the core and on the fuse body for selectively connecting any specific fuse finger with the other contact.
7. A multiple fuse plug, comprising a hollow body supporting a pair of contacts, fuse material within the hollow body and in the form of a base portion connected with one of said contacts and having a plurality of fingers extending from the base portion and within the hollow body, a core within the hollow body and adapted to assume various rotative positions and having a fume chamber for selective location over the fuse fingers, and a means on the core and on the fuse body for selectively connecting any specific fuse finger with the other contact, comprising a spring on the fuse body connected with said other contact, and a ring on said core engaging said spring and having an enlarged portion contacting with the tip of one of said fuse fingers, said ring comprising a strip bent into the ring form and having its ends engaged in a groove on said core for maintaining itself in place.
8. In a multiple fuse plug, a hollow body supporting a shell contact and an end contact, fuse elements supported within said hollow body and within the inner surface of the hollow body and in electrical connection with one of said contacts, a core in intimate contact with the inner surface of the hollow body and restricting passage of flames and arcs between the fuse elements and adapted to assume various rotative positions and having a fume chamber for selective location over the fuse elements, and a contact on said core in electrical connection with the other of said contacts and upon rotation of the core adapted for selective connection with any specific fuse element exposed to the fume chamber.
9. In a multiple fuse plug, a hollow body supporting a shell contact and an end contact, fuse elements supported within said hollow body and within the inner surface of the hollow body and in electrical connection with one of said contacts, a core in intimate contact with the inner surface of the hollow body and restricting passage of flames and arcs between the fuse elements and adapted to assume various rotative positions and having a fume chamber for selective location over the fuse elements, and a contact on said core in electrical connection with the other of said contacts and upon rotation of the core adapted for selective connection with any specific fuse element exposed to the fume chamber.
- Signed at New York, in the county of New York and State of New York, this 25th day of May, A. D. 1931.
- SAMUEL J. WYNN.
